ATTORNEY

UNITED STATES PATENT OFFICE.

FRANZ MEINBERG, OF NEW YORK, N. Y.

DESIGN FOR A BROW AND NECK BAND.

SPECIFICATION forming part of Design No. 12,405, dated August 9, 1881.

Application filed July 7, 1881. Term of patent 7 years.

To all whom it may concern:

Be it known that I, FRANZ MEINBERG, of the city, county, and State of New York, have invented a new and original Design for a Brow and Neck Band, of which the following is a full, clear, and exact description, reference being had to the accompanying drawings, making part of this specification.

This invention relates to an improved design 10 for brow-bands, neck-bands, belts, and similar articles; and it consists of a brow-band, neck-band, or belt, the body of which is arranged with raised side flanges, between which is placed a filling-chain of plain wire links and 15 longitudinally-striped ornamental links.

In the accompanying drawings, which fully represent the nature of my design, Figure 1 represents a perspective view of a brow-band made according to my design; and Fig. 2 is a 20 vertical transverse section of the same on line $x x$, Fig. 1.

Similar letters of reference indicate corresponding parts.

A in the drawings represents a brow-band, 25 neck-band, or belt, which is provided with raised side ribs or flanges, a , and with an ornamental chain, B, which is arranged in the

space formed between the side ribs, a . The chain B is made of broad ornamental links, which are covered with leather of any suitable 30 color, and arranged with longitudinal center bands or stripes and of smaller connecting wire links alternating therewith.

The ornamental links of the chain B impart to the brow-band or other article a striking 35 character, and relieve the rather monotonous appearance of the brow-band with plain chains.

Having thus described my invention, I claim as new and desire to secure by Letters Patent—

A design for brow-bands, neck-bands, and 40 belts, consisting of a base - part, A, having raised side ribs, aa , and of an ornamental chain, B, arranged in the space between the ribs, said chain having broad longitudinally-striped links and plain connecting wire links, substantially 45 as shown and described.

In testimony that I claim the foregoing as my invention I have signed it this 29th day of June, 1881.

FRANZ MEINBERG.
